PREPARATION OF NITRATES OF MONOHYDRIC ALIPHATIC ALCOHOLS

Joseph A. Wyler, Allentown, Pa., assignor to Trojan Powder Company, Allentown, Pa.

No Drawing. Application September 19, 1936,
Serial No. 101,613

6 Claims. (Cl. 260—144)

My invention relates to a process for nitrating monohydric aliphatic alcohols and particularly deals with the nitration of monohydric aliphatic alcohols in the presence of esters of aliphatic monohydroxy carboxylic acids. The principal object of my invention is to provide improved means of preparing nitrates of monohydric aliphatic alcohols.

It is well known that nitric acid reacts with methyl, ethyl, propyl, butyl and amyl alcohols to form nitrates. However, no really satisfactory method for carrying out this reaction between nitric acid and any of these alcohols to form the corresponding nitrates has ever been developed. The yields of nitrated products are low and the operations are too dangerous.

I have discovered that if a monohydric aliphatic alcohol containing less than six carbon atoms be mixed with ethyl lactate, methyl lactate, propyl lactate, butyl lactate, amyl lactate or the corresponding glycolates, that the nitration of the alcohols can be carried out with excellent yields and with safety.

As a nitrating acid I may use a mixture of sulphuric acid and nitric acid, or a mixture of nitric acid and phosphoric acid, or I may use nitric acid alone without the addition of any dehydrating agent.

The general mode of operation is to mix the aliphatic alcohol with the aliphatic hydroxy acid ester in any proportion desired and then to add this mixture to the nitrating acid.

The following examples show more fully how I may carry out my process of nitration:

EXAMPLE NO. 1

Ethyl lactate and methyl alcohol

600 parts of a mixed acid consisting of 40% nitric acid and 60% sulphuric acid are placed in a suitable nitrator, cooled to about 20° C. or less, stirred, and 200 parts of a mixture consisting of 50 parts ethyl lactate and 150 parts methyl alcohol are added slowly, maintaining the temperature below 20° C. for the main portion of the nitration. The mixture is stirred for about one hour after all of the liquid to be nitrated has been added, allowed to run into a separator, where the spent acid forms the lower layer and the nitrated product the upper layer. The upper layer is run into a relatively large amount of water, stirred, separated by settling, washed with a dilute alkali solution until all free acid has been neutralized and then washed with water in order to remove the alkali. The final, neutral product is allowed to separate from its water wash and is then essentially a mixture of nitrated ethyl lactate and propyl nitrate. The yield is 277 parts.

separate from its water wash and is then essentially a mixture of nitrated ethyl lactate and methyl nitrate. The yield is 309 parts.

EXAMPLE NO. 2

Butyl lactate and propyl alcohol

600 parts of a mixed acid consisting of 40% nitric acid and 60% sulphuric acid are placed in a suitable nitrator, cooled to about 20° C. or less, stirred and 200 parts of a mixture consisting of 50 parts ethyl lactate and 150 parts n-propyl alcohol are added slowly, maintaining the temperature below 20° C. for the main portion of the nitration. The mixture is stirred about one hour after all of the liquid to be nitrated has been added, allowed to run into a separator, where the spent acid forms the lower layer and the nitrated product, the upper layer. The upper layer is run into a relatively large amount of water, stirred, separated by settling, washed with a dilute alkali solution until all free acid has been neutralized and then washed with water in order to remove the alkali. The final, neutral product is allowed to separate from its water wash and is then essentially a mixture of nitrated ethyl lactate and propyl nitrate. The yield is 277 parts.

EXAMPLE NO. 3

Butyl lactate and butyl alcohol

1500 parts of a mixed acid consisting of 40% nitric acid and 60% sulphuric acid are placed in a suitable nitrator, cooled to about 20° C. or less, stirred and 500 parts of a mixture consisting of 200 parts butyl lactate and 300 parts butyl alcohol are added slowly, maintaining the temperature below 20° C. for the main portion of the nitration. The mixture is stirred about one hour after all of the liquid to be nitrated has been added, allowed to run into a separator, where the spent acid forms the lower layer and the nitrated product the upper layer. The upper layer is run into a relatively large amount of water, stirred, separated by settling, washed with a dilute alkali solution until all free acid has been neutralized and then washed with water in order to remove the alkali. The final, neutral product is allowed to separate from its water wash and is then essentially a mixture of nitrated butyl lactate and butyl nitrate. The yield is 690 parts.

The examples given show the preferred embodiments of my invention, and are merely illustrative of my process. I may vary the strengths and proportions of acids used in nitrating, the temperature of nitration, the method of adding the liquids

to be nitrated and other operative details which may be advisable under individual conditions, without departing from the essence of this invention.

- 5 It should be noted that although my examples do not mention the use of the glycollates I may use such glycollates as methyl glycollate, ethyl glycollate, propyl glycollate, butyl glycollate and amyl glycollate interchangeably with the lactates, 10 the said glycollates performing all the functions performed by the corresponding lactates.

The finished nitrated product consists essentially of the nitrated alcohol, the nitrated ester of the hydroxy aliphatic carboxylic acid and a 15 small percentage of the unnitrated alcohol started out with. This nitrated product may be used directly in explosives or it may be used as a source of methyl nitrate, ethyl nitrate, etc. which are readily separated by fractional distillation. 20 Certain other particular uses for the mixed nitrates made by my process are as an ingredient of tetranitromethane explosives, plastic explosives, gelatin and waterproof explosives, and as a constituent of fuels for automotive purposes.

25 I claim:

1. The process which comprises nitrating a monohydric aliphatic alcohol of less than 6 carbon atoms in the presence of an alkyl ester of a mono- 25 hydroxy aliphatic carboxylic acid.

30 2. The process which comprises nitrating a monohydric aliphatic alcohol of less than 6 carbon atoms in the presence of a nitrated alkyl ester of a monohydroxy aliphatic carboxylic acid.

3. The process which comprises nitrating a

monohydric aliphatic alcohol of less than 6 carbon atoms in the presence of a nitrated alkyl ester of a monohydroxy aliphatic carboxylic acid, said "alkyl" being a member of the group consisting of the methyl, ethyl, propyl, butyl and amyl groups. 5

4. The process which comprises nitrating a monohydric aliphatic alcohol of less than 6 carbon atoms in the presence of an ester of a monohydroxy aliphatic carboxylic acid, at a temperature of less than 20° C. 10

5. The process which comprises nitrating a mixture of a monohydric aliphatic alcohol of less than 6 carbon atoms and an alkyl ester of a monohydroxy aliphatic carboxylic acid, said mixture 15 containing a substantial proportion of the monohydric aliphatic alcohol by allowing said mixture to flow into a mixed acid consisting of approximately 40% HNO₃ and 60% H₂SO₄, at a temperature less than 20° C. separating the nitrated product from the spent acid, washing and purifying said nitrated product. 20

6. The process which comprises nitrating a mixture of a monohydric aliphatic alcohol of less than 6 carbon atoms and a nitrated alkyl ester of 25 a monohydroxy aliphatic carboxylic acid, said mixture containing a substantial proportion of monohydric aliphatic alcohol, by allowing said mixture to flow into a mixture comprising nitric acid and a dehydrating agent, at a temperature less than 20° C., separating the nitrated product 30 from the spent acid and washing and purifying said nitrated product.

JOSEPH A. WYLER.
